US00D887494S

(12) **United States Design Patent** (10) **Patent No.:** **US D887,494 S**
(45) **Date of Patent:** **** Jun. 16, 2020**

(54) **CHESS BOARD**

(71) Applicant: **Carolyn Hsu**, Laguna Beach, CA (US)

(72) Inventor: **Carolyn Hsu**, Laguna Beach, CA (US)

(**) Term: **15 Years**

(21) Appl. No.: **29/682,999**

(22) Filed: **Mar. 8, 2019**

(51) LOC (12) Cl. **21-01**

(52) U.S. Cl.

USPC **D21/349**

(58) **Field of Classification Search**

CLAIM

The ornamental design for a chess board, as shown and described.

DESCRIPTION

FIG. 1 is an elevational view of the top surface of a chess board in accordance with my new design.

The sides and bottom of the chess board are flat and unornamented. The appearance of the sides and bottom of the chess board form no part of the claimed design.

1 Claim, 1 Drawing Sheet
